Patented December 6, 1904.

UNITED STATES PATENT OFFICE.

GEORGE E. SAVAGE, OF MERIDEN, CONNECTICUT, ASSIGNOR TO
MANNING, BOWMAN & COMPANY, OF MERIDEN, CONNECTI-
CUT, A CORPORATION OF CONNECTICUT.

DESIGN FOR A LEG FOR CHAFING-DISH STANDS.

SPECIFICATION forming part of Design No. 37,254, dated December 6, 1904.

Application filed November 2, 1904. Serial No. 231,155. Term of patent 7 years.

To all whom it may concern:

Be it known that I, GEORGE E. SAVAGE, a citizen of the United States, residing at Meriden, county of New Haven, State of Connecticut, have invented a new, original, and ornamental Design for a Leg for Chafing-Dish Stands, of which the following is a specification.

Figure 1 is an elevation of a leg for a chaf-

ing-dish stand embodying my design. Fig. 2 is a vertical section of the same.

What I claim is—

The ornamental design for leg for chafing-dish stands as shown.

GEORGE E. SAVAGE.
